UNITED STATES PATENT OFFICE.

LESLIE N. CRICHTON, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT BREAKER.

Application filed September 27, 1922. Serial No. 580,787.

My invention relates to circuit breakers and particularly to means for extinguishing arcs that are formed across the relatively movable contact members thereof.

5 The objects of my invention are the provision of means for utilizing magnetic forces incident to the flow of current through the circuit breaker for assisting in the rupture of the circuit, and of means whereby the effectiveness of such forces is substantially proportional to the strength of the current passing through the interrupter.

Another object of my invention is to provide means for causing the arcing tips to 15 turn to their normal positions after the magnetic forces incident to the generation of the arc have ceased.

As shown in the accompanying drawing, Figure 1 is a view, in side elevation, of a 20 portion of a circuit breaker embodying my invention, and

Fig. 2 is a side elevational view looking from the right of Fig. 1.

Only so much of the circuit breaker is 25 shown as is necessary to a clear description of my invention, the apparatus being intended for employment as an oil-type breaker but the oil or quenching fluid tank within which the movable contact members 30 are to be mounted is not shown.

A lifting rod 3 is employed for raising and lowering a bridging member 4 to make and break a circuit across stationary contact members 5 that are secured to conductors 6.

40 Arcing tips 7 are pivotally supported by the conductors 6, upon pins 8, the lower ends of the tips 7 being rounded and mounted to bear against upper side of the bridging member 4. Coiled springs 9—10 are disposed around the pins 8 and the conductors 6 and abut against opposite sides of the arcing tips 7 to yieldingly hold them in the position shown in Fig. 2.

45 As shown in the drawing, the bridging member 4 has been lowered to break the circuit across the stationary contact members 5 and is at the point of separation from the arcing tips 7. Further downward movement of the bridging member will result in the formation of arcs between it and the arcing tips 7.

Electric current, in passing through the conductors 6, arcing tips 7 and bridging

member 4, follows a path of substantially 55 U-shape, thereby creating opposing magnetic forces in the zone lying between the conductors 6 and the arcing tips 7 which tend to bias the arcing tips 7 outwardly about their pivots 8.

If, when the bridging member 4 has been lowered to a position where it no longer engages the arcing tips 7, the current is of sufficient strength, the magnetic forces will move the arcing tips 7, against the tension of the 60 spring portions 9, to the dotted-line positions A carrying with them the arc terminals that have been established upon their lower rounded ends. This movement lengthens the arc streams and causes them to move 65 through the cooling medium within the breaker tank (not shown) and thereby serves to more quickly extinguish the arcs. The magnetic forces, in addition to effecting movement of the arc terminals, also exercise 70 a blowout effect upon the arc streams.

If the current passing through the circuit at the time of rupture is of such small value that no appreciable magnetic forces are set up between the conductors 6, the arcs 75 that are formed will be readily broken by the mere separation of the bridging member and the arcing tips. With currents of greater strength, the magnetic forces will, of course, be proportional thereto, and the 80 length of the path of movement of the arcing tips 7 and the length of the arc streams will increase in proportion to the strength of the magnetic forces.

The portions 10 of the helical spring are 85 put under compression during the outward movement of the arcing tips 7 as portions 9 of the spring are held between the bases of the conductors 6 and the stop members 11. By this arrangement, portions 9 press upon 90 the arcing tips 7 during the first part of their rotation but, upon spring portions 9 striking the stop members 11, further movement of the spring parts 9 being thereby prohibited, the arcing tips 7 are carried through 95 the remaining arcs by the magnetic blowout forces.

100 Stop members 12 limit the extreme outward position of the arcing tips 7. After the arcing tips have reached their extreme positions, as shown in the dotted-line position A of Fig. 1, and the magnetic blowout forces have ceased to exist, the compression

of the spring portions 10 cause the arcing tips to turn into a normal position, shown in full lines. As the bridging member 4 is drawn upward in the operation of closing contact, arcing tips 7 are encountered and are carried upward to the dot-and-dash position B against the tension of spring portion 9 where they remain so long as the contacts are closed.

10 While my invention is intended primarily for circuit breakers of the oil type, it may also be utilized in connection with breakers of the carbon or air-break type.

15 Various modifications and changes may be made without departing from the spirit and scope of the invention, as defined by the accompanying claims.

I claim as my invention:

20 1. The combination with a pair of relatively movable main contact members, of an arcing tip pivotally supported adjacent to one of the said members, means for yieldingly holding the arcing tip at a predetermined position when the main contact members are separated, the contact members and the arcing tip being disposed for creating repellent magnetic forces to effect movement by the arcing tip beyond the said position during the opening operation of the circuit 25 interrupter.

25 2. In a circuit interrupter, an arcing tip comprising a finger member, a shaft at an angle thereto, a spiral spring mounted on said shaft, means for tensioning and limit-

ing the rotation of said spring, the end portions of said spring being bent to engage the opposite sides of said finger, whereby movement of said finger is controlled during the opening and closing of said circuit interrupter.

3. In a circuit interrupter, a pair of relatively movable contact members, an arcing tip normally disposed in alignment with the contact members when in their open position, and resilient means for biasing the arcing tip to the normal position, the resilient means being stressed during the closing operation of the interrupter whereby the arcing tip tends to snap beyond its normal position upon the opening of the circuit interrupter.

4. In a circuit interrupter, a pair of relatively movable contact members, an arcing tip normally disposed in alignment with the contact members when in their open position, and resilient means for biasing the arcing tip to the normal position, the resilient means being stressed during the closing operation of the interrupter whereby the arcing tip tends to snap beyond its normal position upon the opening of the circuit interrupter under the combined influences of the resilient means and magnetic forces.

In testimony whereof, I have hereunto subscribed my name this 20th day of September, 1922.

LESLIE N. CRICHTON.
